DISPLAY DEVICE
Meyer M. Brown, 261 Broadway, New York, N.Y.
Filed June 26, 1963, Ser. No. 290,844
5 Claims. (Cl. 40—62)

The present invention relates to display devices and, more particularly, to a display device of the kind in which a message such as a pictorial presentation visible in a window of the device can be changed to the other pictorial representation in a concealed manner.

Display devices of the kind above referred to are useful for informative, promotional and entertainment purposes.

It is a broad object of the invention to provide a novel and improved display device of the general kind above referred to in which the message appearing in the window of the device is gradually changed in a surprising and concealed manner.

A specific object of the invention is to provide a novel and improved display device in which pliable strips bearing the pictorial representations or other messages alternately visible in the window of the device are guided and held taut by a floating slide whereby transition from one pictorial representation to the other can be effected in a smooth, simple and concealed manner by sliding an actuating member of the device from one limit position to another one.

Another specific object of the invention is to provide a novel and improved display device of the general kind above referred to in which manipulation of the device successively exhibits different sets of printed information which may be associated with the pictorial representations, or independent therefrom.

It is also a specific object of the invention to provide a novel and improved display device which can be conveniently and inexpensively manufactured in that all of the components of the device consist of blanks which may be stamped out of paper or other suitable material and can be joined by folding and gluing operations.

Other and further objects, features and advantages of the invention will be pointed out hereinafter and set forth in the appended claims constituting part of the application.

In the accompanying drawing several embodiments of the invention are shown by way of illustration and not by way of limitation.

In the drawing:

FIG. 1 is an elevational front view of the device showing one message fully visible in the window of the device.

FIG. 2 is a view similar to FIG. 1 showing the transition from one message to another.

FIG. 3 is a view similar to FIG. 1 and showing the second message fully visible in the window.

FIG. 4 is an exploded view of the device.

FIG. 5 is a perspective detail view of the device in partly cut-open and unfolded condition.

FIG. 6 is a view similar to FIG. 5 but showing the components of the device in a different operational condition.

FIG. 7 shows stops means for limiting the outward movement of the operating slide of the device to the position shown in FIG. 3.

FIG. 8 is an elevational front view of a modification of the display device, and

FIG. 9 shows the device of FIG. 8 in a different operational position.

Referring first to FIGS. 1, 2 and 3, the display device according to the invention as exemplified in these figures comprises an envelope 10 of generally rectangular shape. The envelope may be made of any suitable material, generally strong paper or thin cardboard. The face side of

the envelope which is visible in FIGS. 1, 2 and 3 includes a window 15 of any suitable configuration, a window having a generally rectangular shape being shown. A slide 50 also made of strong paper, thin cardboard or other suitable material is slidable into and out of the envelope. Displacement of the slide in reference to the envelope causes one of two messages to be visible in the window. The two messages are symbolized by letters A and B. In practice the messages may and usually will consist of two pictorial representations which may be of informative, promotional or entertaining nature. The messages may also consist of appropriate printed data. Generally speaking, there is no limitation on the nature of the message, provided only that it can be made visible in window 15. It is also not necessary that the entire message be visible in the window at one time. Successive parts of a message may be exhibited in the window as the slide is displaced.

FIG. 1 shows operating slide 50 pushed fully into envelope 10 and the message A is exhibited.

FIG. 2 shows the slide partly pulled out and in a position in which the message A is disappearing and the second message represented by letter B is beginning to appear.

FIG. 3 shows the slide fully pulled out and the entire message B is now visible in the window.

Return of the slide from the position of FIG. 3 into the position of FIG. 1 causes the message B to disappear gradually and the message A to appear gradually until finally the message A is again fully visible.

The manner in which the transition from one message to another in a concealed manner is effected by manipulation of slide 50 will now be described in detail in connection with FIGS. 4 through 7.

Referring to FIG. 4 which shows the display device in exploded form, envelope 10 comprises a face sheet 11 and a back sheet 12 joined along a fold line 13. Face sheet 11 is formed with a bottom flap 16 folded over and glued to back sheet 12 along a strip 17, preferably so that the back sheet 12 is on the outside of the flap. Flap 17 is cut at 18 through part of its width and the cut upper portion 18a of the flap is bent back and glued against the inside of flap 16 to form a double layer at the inside of the flap. This double layer constitutes a stop edge 19 for a purpose which will be more fully explained hereinafter. Face sheet 11 is further formed with an end flap 20 upon which is glued back sheet 12 along a strip 21. As it is now apparent, the envelope constitutes a pocket closed at three sides but open along its edge 11a when the face sheet and the back sheet are glued together as described. Finger grip recesses 25 and 25a are provided in the face sheet and the back sheet. These two recesses are in registry when the envelope is glued as can be clearly seen for instance in FIGS. 1, 2 and 3.

The operating slide 50 is also of rectangular configuration, the general dimensions of the slide being such that the same can be accommodated in the envelope, as is shown in FIG. 1. The slide is cut out along one of its longitudinal edges to form a shoulder 27 coacting with stop shoulder 19 in a manner and for a purpose which will be explained hereinafter. The opposite lengthwise side of the slide may also be set off at 28 so that the portion of the slide pulled out of the envelope as shown in FIGS. 2 and 3 is of uniform width.

The display device further comprises two pliable strips 30 and 31. The two strips may be made of a suitable smooth, thin and adequately strong paper, but they may also be made of a fabric. End 30a of strip 30 is secured to the inside of face sheet 11 at 32, preferably by gluing and the other end 30b of strip 30 is secured to slide 50 at 33, preferably also by gluing. Similarly, one end 31a of strip 31 is secured to the inside of face sheet 11 at 34, preferably by gluing and the other end 31b of strip 31 is secured to slide 50 at 35, preferably by gluing. To

facilitate attachment of strip end 31b to slide 50 without subjecting the strip to wear due to engagement with flap 20, slide 50 is cut out at 36 and the strip end 31b is folded over the cut-out portion 36.

The two strips are bearing the aforescribed messages symbolized by letters A and B. As it is apparent, window 15 is placed somewhat out of center in the exemplified embodiment. To compensate for such displacement of the window, strip 30 is somewhat longer than strip 31.

The display device finally comprises a guide slide 40. This slide which may be made of a paper of sufficient rigidity or also of thin plastic has a slot 41 extending transverse of the direction of movement of operating slide 50, as shown in FIGS. 1, 2 and 3 and is of a length sufficient to accommodate strips 30 and 31. The two strips extend through slots 41 in a manner best shown in FIGS. 5 and 6. As it is apparent, the two fold lines thus formed in the strips are located within slot 41 and each strip will straddle the respective lengthwise edge of slot 41. The lengths of the strips and the points of attachment thereof are so correlated that guide slide 40 will hold taut the strips at all times and guide the same when passing through the slot.

As it is apparent, the fold lines of the two strips are separated in the slot by a gap depending upon the width of the slot. This separating gap will be visible when and while slide 40, or more specifically the slot thereof is exposed in window 15. To conceal the gap and with it the separation between the two strips, a cover strip 60 is provided. The strip is attached to guide slide 40 on the side thereof adjacent to the inside of face sheet 11. The attachment of the cover strip to slide 40 is such that the two strips can pass between cover strip 60 and the respective side of slide 40 into and through slot 41 thus concealing the separation between strips 30 and 31.

Cover strip 60 may be secured to guide slide 40 in any suitable manner. It has been found advantageous to provide an upper tongue 61 and a lower tongue 62 on the cover strip. These two tongues are bent over the respective edges of guide slide 40 which is formed with recesses 40a and 40b to accommodate the tongues as it is clearly shown in FIGS. 5 and 6. The tongues are shown to be lengthwise elongated to form smooth guide surfaces for message strips 30 and 31 as the same move along guide slide 40. The tongues further serve the purpose of reinforcing the guide slide at the portions at which it is most weakened by slot 41. As may be observed, there are three thicknesses, namely the thickness of the guide slide proper, the thickness of the shield portion 60a of strip 60 and the thickness of tongues 61 and 62 respectively. FIGS. 5 and 6 show guide slide 40 straddled by message strips 30 and 31 and the cover strip 60 attached to the slide. The figures also show all the components of the device in their functional positions, though it should be understood that in FIGS. 5 and 6 the components are still somewhat pulled apart to show more clearly the coaction of the components.

FIG. 7 and also FIGS. 1, 2 and 3 show the fully assembled display device.

The operation of the display device as hereinbefore described is as follows:

The position of operating slide 50 as shown in FIG. 5 corresponds to the position of the slide in FIG. 1, that is the slide is completely pushed into envelope 10 and letter A is exposed in window 15. When the slide is now pulled out, that is pulled from the position of FIG. 5 into the position of FIG. 6 which corresponds to FIG. 3, slide 50 will pull the portion of strip 30 located between slide 50 and guide slide 40 outwardly, thereby gradually increasing this strip portion in length and correspondingly decreasing the length of the portion of strip 30 located between guide slide 40 and the face sheet 11 and secured to the latter. Similarly the length of the portion of strip 31 located between face sheet 11 and guide slide 40 increases and the length of the portion of strip 31 located between

guide slide 40 and back sheet 12 decreases. Due to these changes in the lengths of the strips, portions on opposite sides of guide slide 40, the guide slide is compelled to move toward the open side 11a of the envelope when and while slide 50 is being pulled out and to move in the opposite direction when the slide is pushed in. The displacement of the guide slide in either direction causes continuously changing portions of one or the other strip to be exposed in the window and also the gap between the two strips to travel past the window. However, the gap is concealed by the shielding or cover strip 60 as previously described. Accordingly, a person observing the window will first see one message in the window. This message will appear to be gradually wiped out by strip portion 60a traveling across the same and to be gradually replaced by appearing portions of the second message. Accordingly, there are intermediate stages, one of which is indicated in FIG. 2 in which both messages are partly exposed in the window (see FIG. 3). The opposite operations takes place when the slide is pushed in.

As is clearly shown in FIGS. 5, 6 and 7, the outward movement of slide 50 is limited by engagement of shoulder 27 with stop edge 19. The stop means may be arranged in various ways, for instance a tongue may be bent out of the lefthand edge of face sheet 11, or a piece of material may be glued to the face sheet or the back sheet in the appropriate position.

According to FIGS. 8 and 9, the movement of slide 50 is utilized to exhibit additional messages. To this end a second window 70 is provided in face sheet 11 and/or the back sheet. Intelligence indicated at 71 is printed or otherwise provided on slide 50 or on strip 30 and such additional information will appear section by section when and while the slide is pulled out or pushed in. The message printed on the slide or the strip may be supplemented by data appearing on the outer side of the face sheet or the back sheet adjacent to window 70. The additional information exposed in window 70 may be associated with the messages exposed in window 15 or may be independent therefrom. For instance, the messages exposed in window 15 may be in the form of technical components and the information appearing in window 70 may contain data pertinent to the technical components, or other data of interest.

While the invention has been described in detail with respect to certain now preferred examples and embodiments of the invention, it will be understood by those skilled in the art after understanding the invention, that various changes and modifications may be made without departing from the spirit and scope of the invention, and it is intended therefore to cover all such changes and modifications in the appended claims.

What is claimed as new and desired to be secured by Letters Patent is:

1. A display device comprising, in combination, a base sheet including a window, an actuating sheet rectilinearly slidable in either direction along the base sheet parallel thereto between a limit position in substantial superimposition with the base sheet and a limit position laterally spaced from one end thereof, a first transversely folded pliable strip bearing thereon a first message, a second transversely folded pliable strip bearing thereon a second message, both said strips being interposed between said sheets and secured at one end to the base sheet on opposite sides of the window in the direction of movement of the actuating sheet and at the other ends to opposite ends of the actuating sheet, the folded edges of said strips facing each other, a slide interposed between said sheets and having a slot extending transverse of the direction of movement of said actuating sheet and parallel to the fold lines of said strips, each of said opposite strips extending through said slot and straddling the lengthwise edges of the slot, said slide tensioning and guiding both the strips and being floatingly supported by the same, and a cover

strip extending transversely across the slide and covering the slot thereof on the side adjacent to the base sheet, the portions of the two pliable strips facing the base sheet passing into the slot underneath said cover strip, displacement of the actuating sheet in either direction in reference to the base sheet causing said slide to be drawn past said window thereby exposing varying portions of the two strips bearing alternate messages in the window, said cover strip concealing the folded edges of the strips juxtaposed in the slot, said cover strip having end portions folded over the respective edges of the slide for securing the cover strip to the slide, said folded-over strip portions reinforcing the slotted portions of the slide.

2. A display device according to claim 1 wherein at least one of the folded-over portions of the cover strip constitutes a guide for the pliable strips.

3. A display device comprising, in combination, a generally rectangular envelope having a face sheet and a back sheet and being open along one of its sides, the face sheet including a window, an actuating slide within said envelope lengthwise slidable in either direction in reference to one end of the envelope for partially moving the slide into and out of the envelope through the open side thereof, a first transversely folded pliable strip bearing thereon a first message, a second transversely folded pliable strip bearing thereon a second message, both said strips being interposed between said face sheet and said actuating slide and secured at one end to said face sheet on lengthwise opposite sides of said window and at the other end to opposite lengthwise ends of the slide, the folded edges of the strips facing each other, a guide slide interposed between said face sheet and said actuating slide and having a slot extending transverse of the envelope, each of said opposed strips extending through that slot and straddling the side edges thereof, said guide slide tensioning and

guiding both the strips and being floatingly supported by the same, and a cover strip extending across said guide slide and covering the slide thereof on the side of the slide adjacent to the face sheet, the portions of the slidable strips adjacent to the face sheet passing into said slot and to the opposite side of the guide slide underneath said cover strip, lengthwise displacement of the actuating slide in reference to the envelope causing said guide slide to be drawn past said window, thereby exposing varying portions of the two strips bearing alternate messages in the window, said cover strip concealing the folded edges of the strip juxtaposed in the slot.

4. A display device according to claim 1 wherein said cover strip has end portions folded over the respective edges of the guide slide for securing the cover strip to the guide slide, said folded-over cover strip portions reinforcing the slotted portions of the guide slide.

5. A display device according to claim 1 wherein one of said sheets includes a second window and bears intelligence adjacent thereto, and wherein at least one of said pliable strips bears several sets of intelligence spaced lengthwise in the direction of movement of the strips, any selected one of said sets being movable into registry with said second window by displacing said actuating slide.
